CLAIM

The ornamental design for a “stuffed toy potbelly pig”, as shown and described.

DESCRIPTION

FIG. 1 is a pictorial view of the stuffed toy potbelly pig showing my new design;

FIG. 2 is a top plan view thereof;

FIG. 3 is a side elevation view thereof, the opposite side being a mirror image thereof;

FIG. 4 is a rear elevation view thereof;

FIG. 5 is a front elevation view thereof; and,

FIG. 6 is a bottom plan view thereof.
